(57) CLAIM

The ornamental design for a speaker for home theater, as shown and described.

DESCRIPTION

FIG. 1 is a perspective view of a speaker for home theater showing our new design;

FIG. 2 is a front view thereof;

FIG. 3 is a rear view thereof;

FIG. 4 is a left side view thereof where the right side view is a mirror image;

FIG. 5 is a top plan view thereof;

FIG. 6 is a bottom plan view thereof; and,

FIG. 7 is a perspective view showing the state in which the upper part thereof has been detached and then can be used in a separate place.

1 Claim, 6 Drawing Sheets
